UNITED STATES PATENT OFFICE.

PETER JOHNSON, OF WAUCONDA, ILLINOIS.

GAME.

SPECIFICATION forming part of Letters Patent No. 425,100, dated April 8, 1890.

Application filed November 7, 1889. Serial No. 329,515. (No model.)

To all whom it may concern:

Be it known that I, PETER JOHNSON, a citizen of the United States, residing at Wauconda, in the county of Lake and State of Illinois, have invented a new and useful Improvement in Games, of which the following is a specification.

My invention relates to the class of games played with "men" on a "board;" and my object is to provide in the said class an improved game in the sense of its affording entertainment of the kind experienced in the playing of other games of its class, but augmented by its novelty.

My improved game is particularly adapted to be played simultaneously by four players, forming two sets of partners seated opposite each other with the board between them, though it affords entertainment to three, playing each for himself, or even for two players.

The game involves the use of a board, like or substantially like that presented in the accompanying drawing, men, and dice. The men and dice are not presented in the drawing, as they contain no features of novelty, might tend to confusion in the representation, and because the game may, without illustrating them, be readily understood from the following description:

A is the board, which may be, generally speaking, of the form of a checker or back-gammon board, thus involving a rectangular board of suitable material adapted, as preferred and illustrated, (though not necessarily,) to be folded upon itself along a central line α , and having appropriately provided upon its surface indications for the placing of the men.

My game involves the provision of the board A, on the surface thereof upon which the game is played, with circles, one within the other, four such circles, denoted, respectively, by the letters r , q , p , and o , and concentric, being shown and preferred, though that number may be increased or diminished without destroying the utility of the board for my purpose. The circles afford intervening spaces n , m , and l , each of which is marked off into as many parts or arcs as there are or are intended to be players, preferably four, as this is the maximum number of players for which the game is intended, and the divisions are

indicated in the spaces n , m , and l , respectively, by the spots s , s' , and s^2 , arranged radially, as shown, and which should be designated by the numbers 1, 2, and 3. Between the radially-arranged series of numbers 1, 2, and 3 the spaces n , m , and l are provided at intervals, preferably equal, with spots k , k' , and k^2 , arranged in radial series, as shown, there being in each division of the board the same number of series, it being the number thereof shown and preferred, though the game may be prolonged or shortened by increasing or decreasing the number.

Within the innermost circle o is a rectangular figure i , having within it a similar figure i' , the angles of the two figures being in radial line with each other and with the series of spots s , s' , and s^2 . Between each angle (shown to be blunted in the drawing) of the figure i and the adjacent spot s^2 is a spot s^3 , and between each pair of adjacent angles of the figures i and i' is a spot s^4 , and inside the figure i' , at each of its angles, and thus in radial line with the spots s to s^4 , is a spot s^5 .

The concentric rectangular figures i and i' afford the spaces h between them, each of which contains between the spots s^4 at its extremities, the spots s^6 , s^7 , and s^8 . Each series of spots from and including s^8 to s^7 , included, is shown to be numbered in series—that is, respectively, 4, 5, 6, 7, and 8, and each spot s^9 is shown to be numbered 9. This, however, is not necessary, the said numbers being only indicated, in the present connection, to facilitate understanding of the manner of playing the game, hereinafter described; nor are the figures i and i' indispensable, as the spots arranged with reference to them could be so arranged without the outlines of the figures.

The manner of playing the game will be best understood by an explanation thereof, supposing four players to be engaged in it: Each player is provided with three men and a king, and a dice-box and one die should be provided for each player. The men and kings may be of any suitable form or forms—like those in the game of checkers, for example—though the men should be marked to correspond with the spots s , s' , and s^2 , as with the numbers 1, 2, and 3, and the kings should have some distinguishing-mark, and the set of men and the king for each player

should be distinguished from the others, as by being colored differently. On beginning the game each player places his men in position on the series of spots s , s' , and s^2 assigned to him and his king on the respectively adjacent spot s^3 . The men are always played toward the right, and none is allowed to leave its respective circle until it shall have completed its circuit of the board. A play consists in the player throwing his die and moving one of his men toward the right as many spots k , k' , or k^2 on the circle as the number indicated on the upturned side of the die. Men of different players may pass each other in making their circuits, except when "blockaded" by three men being in a row on adjacent spots of the same circle or in radial line across the circles, and men may be moved in making the circuit to capture those of an opponent player and thus send the latter back as many spots or "points" as they were moved forward, thus producing an exchange of places. On completing the circuit, but not before, a man may be moved toward the center of the board, the first man completing the circuit being moved in playing by any of the spots 4, 5, 6, and 7 leading from the series 1 2 3 to the spot 8, where the man stops. As the other men complete their respective circuits, they are passed in playing by way of the spots 4 and 5, respectively, to the spots 7 and 6. It must be understood, however, that no man is permitted to be moved from the end of a circuit out of a circle to a spot 4 while obstructed by a man or king on any of the spots 2, 3, or 4; but when a man or king reaches the respective spot 4, such man or king is safe from molestation and cannot be returned to any of the circles, nor can men throughout the game molest kings. A king comes into play from its initial position on a spot 9 as soon as any or all of the spots 1 2 3 are open, when the player may place his king thereon, provided that in throwing his die he turns up a six-spot. Then he may throw a second time, (otherwise being confined throughout the game to a single throw at each turn,) and should the player, with his second throw, turn up another six-spot, he loses both plays, his king then being returned to the initial position 9. Should the player, however, by his second throw of the die turn up other than a six-spot, he may then move either his king or a man accordingly. Kings may be moved either toward the right or the left, and also diagonally across the circles from spot to spot therein, and a king need not be on the same circle with a man to capture the latter, nor with another king to permit capture thereof. Capture of one king by another sends the captured king back to the starting-point at the respective spot 9, whence the respective player may only remove it on again turning up a six-spot in throwing his die, as hereinbefore explained.

In playing for the "home" position (which

is on the spots s^5 , s^6 , and s^7) a king is not allowed to be moved diagonally across the circles in order to gain or avoid a spot thereon, but must be passed out on the circle to which such king was last moved. If, however, after a king has been moved to a position on a spot 1, 2, or 3 on the way to the home position, the player be not satisfied with the number he turns up in throwing his die or finds he cannot move as many spots as the number on the die indicates, he must then move to the right or left or diagonally, as hereinbefore stated.

A king must not be moved from the circles toward the home position until preceded by all the men of the respective player having been moved in playing to the spots 6, 7, and 8. Then the king is played to the spot 5, which is the home position for the king. The game is then completed and is won by the party or parties first succeeding in getting the home positions of men and king or kings.

The parts shown and described as circles, though preferred in the circular form, are not necessarily such, but may be of other shape, the term "circle" employed in the claims being intended to be considered sufficiently generic to include any analogous means of affording guide-tracks for the movements of the men.

What I claim as new, and desire to secure by Letters Patent, is—

1. A game-board A, provided on its surface with circles, one within the other, affording spaces between them, and divided into sections by spots, as the spots s , s' , and s^2 , and having intermediate series of spots k , k' , and k^2 , and a home for the men and kings within the innermost circle, substantially as and for the purpose set forth.

2. A game-board A, provided on its surface with circles, one within the other, affording spaces between them, each divided into sections by spots, as the spots s , s' , and s^2 , and having intermediate series of spots k , k' , and k^2 , spots s^3 in the innermost circle, each in radial line with a series of the said spots s , s' , and s^2 , and series of home spots s^4 , s^5 , s^6 , and s^7 within the innermost circle, one said series leading from each spot s^3 , substantially as and for the purpose set forth.

3. A game-board A, provided on its surface with circles, one within the other, affording spaces between them, each divided into sections by spots, as the spots s , s' , and s^2 , and having intermediate series of spots k , k' , and k^2 , spots s^3 in the innermost circle, each in radial line with a series of the said spots s , s' , and s^2 , spots s^8 , one in radial line with each spot s^3 , and series of home spots s^4 , s^5 , s^6 , and s^7 within the innermost circle, one said series leading from each spot s^3 , substantially as and for the purpose set forth.

4. A game-board A, provided on its surface with four concentric circles affording the three spaces n m l , marked off, each into four sections by spots s , s' , and s^2 , arranged radi-

ally, a series of six spots extending between each pair of the series of sectional spots s , s' , and s'' in each said space, and arranged radially, a rectangular figure within the innermost circle having each of its angles in radial line with a series of the said sectional spots, a spot s^3 between each said angle and the innermost circle, a series of four spots s^4 , s^5 , s^6 , and s^7 , arranged along each side of the rectangular figure, and spots s^8 within the said figure, substantially as and for the purpose set forth.

PETER JOHNSON.

In presence of—

J. W. DYRENFORTH,
M. J. FROST.
